UNITED STATES PATENT OFFICE.

HENRY W. FIELD, OF COLUMBUS, OHIO.

DESIGN FOR A SWORD-HILT.

SPECIFICATION forming part of Design No. 23,820, dated November 27, 1894.

Application filed October 5, 1894. Serial No. 525,040. Term of patent 7 years.

To all whom it may concern:

Be it known that I, HENRY W. FIELD, a citizen of the United States, residing at Columbus, in the county of Franklin and State of Ohio, have invented and produced a certain new and original Design for Sword-Hilts, of which the following is a specification, reference being had to the accompanying drawing hereto annexed and forming part thereof.

10 The drawing represents a face view of a sword hilt,—this view being deemed sufficient to fully illustrate my design.

15 The leading features of my design consist in two oppositely projecting hilt portions having the form of slightly curved half leaves and scroll extensions of said leaf shaped projections, which lead inward to the guard plate.

20 *a* represents the oppositely extending hilt arms each of which has substantially the form of a half leaf, the central rib of which is curved, as shown.

b represents a substantially shield shaped guard plate which depends from between said hilt projections said guard plate having an embossed or raised border of leaf scroll work, 25 as indicated at *b'*. From the ends of the leaf portions of the hilt projections *a*, extend downward and thence inward scroll arms *c* the inner ends of which meet the shield *b*. Upon the face of the shield *b* is formed in relief the figure of a mounted knight, from which extend radially lines representing light rays.

What I claim is—

20 The design for a sword hilt herein shown 35 and described.

HENRY W. FIELD.

In presence of—

C. C. SHEPHERD,
C. M. VOORHEES.
